UNITED STATES PATENT OFFICE.

WILLARD F. RICHARDS, OF DEPEW, NEW YORK, ASSIGNOR TO GOULD COUPLER COMPANY, OF NEW YORK, N. Y.

RAILWAY-CAR TRUCK.

1,084,297.

Specification of Letters Patent.

Patented Jan. 13, 1914.

Application filed January 13, 1913. Serial No. 741,615.

To all whom it may concern:

Be it known that I, WILLARD F. RICHARDS, a citizen of the United States, residing at Depew, in the county of Erie and State of New York, have invented a new and useful Improvement in Railway-Car Trucks, of which the following is a specification.

This invention relates to car truck side frames, and more particularly to metal side frames of that kind, now well known, which are provided at their opposite ends with integral depending jaws or parts which straddle and hold the journal boxes in place in such a manner that the journal boxes, together with the car wheels and axles, can be readily removed from the truck by raising or jacking up the side frames.

Both the truck frames and the journal boxes are ordinarily made of cast metal, and it is necessary for the manufacturer, in order to meet competition, to so construct the parts that no machining will be required. Since castings, even if made from the same pattern, frequently vary slightly in size, and the surfaces thereof are more or less rough and uneven, it has been customary to construct these parts so that there will be sufficient clearance between the engaging portions to allow the boxes to enter between the jaws notwithstanding the unavoidable variations in size and the roughness of the surfaces of the parts. This results in an objectionable looseness of the parts, allowing them to move relatively to each other with consequent wear.

The objects of the invention are to make car truck side frames and journal boxes of this type in such form that they will fit properly without objectionable looseness or play between the parts; also to provide simple and inexpensive retaining means for preventing the accidental dropping of the journal box from between the frame jaws.

In the accompanying drawings: Figure 1 is a side elevation, partly in section on line 1—1, Fig. 2, of a car truck embodying the invention. Fig. 2 is an enlarged fragmentary plan view thereof, partly in section on line 2—2, Fig. 1. Fig. 3 is a vertical sectional elevation on line 3—3, Fig. 1.

Like reference characters refer to like parts in the several figures.

A represents the metal side frame of a car truck which is provided at each end with integral depending portions *a a'* forming

rigid jaws which straddle and hold the journal box B. Except as hereinafter mentioned, the side frame and journal box may be of any suitable construction, the side frame preferably consisting of a single steel casting of the form shown in the drawings. The depending jaws *a a'* of the side frame preferably do not extend downwardly to the full depth of the journal box, so that the side frame need not be raised or jacked up so high as would otherwise be necessary to disengage the jaws from the journal box, thus greatly facilitating the removal of the journal boxes, axles, and wheels from the car truck. In order to hold the journal boxes from movement laterally or sidewise relative to the side frame, the jaws, in the construction shown in the drawings, are provided at the portions thereof next to the journal box with vertical flanges C C which embrace projecting ribs C' formed on the sides of the journal box.

In order to insure a snug fit between the projecting ribs C' of the journal box and the jaws of the side frame, to prevent movement of the journal box lengthwise of the side frame, the outer faces D of the ribs C' and the opposing faces D' of the jaws which contact therewith are made to incline or converge upwardly slightly. The clearance usually required between the engaging faces of the side frame jaws and the journal boxes can thus be considerably reduced, because the slight variations or inequalities in the interfitting parts which would prevent a journal box from entering between jaws having parallel perpendicular inner faces would not prevent the insertion of the journal box between the jaws in the construction shown, as the inner faces of the jaws are spaced farther apart at their lower ends than at their upper ends. Preferably the interfitting parts are so proportioned that roughness of the contacting surfaces will prevent the complete seating of the journal box between the jaws. The fit of the parts is, however, not so tight but that the vibration and jarring of the truck when it is first run for a few miles on the road, together with the pressure on the faces due to the inclination of the sides, will wear the contacting surfaces smooth and thus allow the journal boxes to enter fully into the space between the jaws so that the side frame will rest and bear firmly on the tops of the jour-

nal boxes, thereby relieving the jaws from pressure due to any wedging action of the boxes. There will then be substantially no clearance between the journal boxes and the side frame, thereby avoiding to a large extent the wear on the contacting surfaces, and the journal boxes will be held firmly in place. The inclination of the contacting faces D D' of the journal boxes and jaws is very slight, not sufficient to cause any appreciable tendency for the side frame to creep upwardly on the journal boxes.

Means are preferably employed for preventing the accidental dropping out of the journal boxes from between the jaws of the side frames. In the construction shown for this purpose, tapered retaining pins or keys E are provided, which extend through registering slots in the side frame and in the projecting rib C' of the journal boxes. The pins are preferably prevented from accidental displacement, for instance by slitting and spreading or swaging the small ends of the retaining pins or keys. Any other device may be employed for holding the journal boxes on the side frame.

It will be understood that side frames and journal boxes provided with the inclined engaging faces can be used without the described holding means, or with holding means other than those described.

I claim as my invention:

1. The combination of a car truck side frame having depending jaws, and a journal box straddled by said jaws, coöperating parts on said jaws and said journal box for holding the journal box from lateral movement relatively to said side frame, the engaging faces of said jaws and journal box converging upwardly, substantially as set forth.

2. The combination of a car truck side frame having jaws, and a journal box straddled by said jaws, said journal box having projecting vertical ribs at opposite sides which are adapted to enter into channels in said jaws for holding the journal box against lateral movement relatively to the side frame, the outer faces of said ribs and

the opposing faces of the channeled portions of said jaws converging upwardly, substantially as set forth.

3. The combination of a car truck side frame having a pair of integrally depending jaws at each end thereof, the opposing faces of each of said pairs of jaws converging upwardly and having vertical flanges at their opposite sides, and journal boxes, each of which is straddled by a pair of said jaws, said journal boxes having projecting ribs, the outer faces of which converge upwardly and which are adapted to enter between the flanges of said jaws, substantially as set forth.

4. The combination of a car truck side frame having jaws, and a journal box adapted to enter between said jaws, the inner faces of said jaws engaging the sides of the journal box to hold the same from movement relatively to the side frame lengthwise thereof, said journal box having projecting vertical ribs at opposite sides which are adapted to enter into channels in said jaws for holding the journal box against lateral movement relatively to the side frame, and holding means extending through said jaws and said ribs for preventing the removal of said box from said jaws, substantially as set forth.

5. The combination of a car truck side frame having jaws, and a journal box adapted to enter between said jaws and to be held thereby against movement relatively to the side frame lengthwise thereof, said journal box having projecting vertical ribs at opposite sides which are adapted to engage with box from lateral movement relatively to said flanges on the jaws for holding the journal side frame, and pins extending through said ribs and said flanges for preventing the removal of said box from said jaws, substantially as set forth.

Witness my hand, this 23d day of Dec., 1912.

WILLARD F. RICHARDS.

Correction in Letters Patent No. 1,084,297.

It is hereby certified that in Letters Patent No. 1,084,297, granted January 13, 1914, upon the application of Willard F. Richards, of Depew, New York, for an improvement in "Railway-Car Trucks," an error appears requiring correction as follows: Page 2, transpose lines 87 and 88; and that the said Letters Patent should be read with this correction therein that the same may conform to the record of the case in the Patent Office.

Signed and sealed this 27th day of January, A. D., 1914.

[SEAL.]

J. T. NEWTON,

Acting Commissioner of Patents.
